ADJUSTABLE STAPLING MACHINE

Bernard Edward Shlesinger, Jr., Falls Church, Va.

Application April 20, 1954, Serial No. 424,298

17 Claims. (Cl. 1—3)

This invention relates to improvements in stapling machines, punches and the like of the type generally referred to as "desk" staplers or punches and is co-pending application with my application Serial No. 356,540, filed May 21, 1953, now Patent No. 2,676,318, issued April 27, 1954.

Present machines are limited in use by the depth of their throat. Business offices are constantly being faced with the problem of stapling papers at points remote from their edge and beyond the scope of the machines now available.

It is an object of this invention to provide a stapling machine or the like capable of stapling at points remote from the edge of the paper.

It is a further object of this invention to provide a stapling machine that is no larger than those presently in use, but which is capable of stapling at remote points.

A still further object of this invention is to provide a stapling machine for clerical use that has an adjustable throat.

Another object of this invention is to provide an adjustable stapling machine that is compact.

Yet another object of this invention is to provide an adjustable stapling machine, without sacrificing staple capacity.

A further object of this invention is to provide a stapling machine which is automatically extensible.

A still further object of this invention is to provide an adjustable stapling machine that is rugged and economical to manufacture.

Another object of this invention is to provide a stapling machine having an adjusting mechanism that will not interfere in any manner with the operation of the machine.

These and other objects and advantages of this invention will be apparent from the following description and claims.

In the accompanying drawings which illustrate by way of example various embodiments of this invention:

Fig. 1 is a side elevation of a stapler embodying this invention and showing the stapler in closed position;

Fig. 2 is an enlarged view, with parts broken away and parts in section.

Fig. 3 is a sectional view along line 3—3 of Fig. 2.

Fig. 4 is a perspective view of the releasing spring.

Fig. 5 is a perspective view of a spring retainer.

Fig. 6 is an enlarged sectional view taken along line 6—6 of Fig. 1.

Fig. 7 is an enlarged sectional view on line 7—7 of Fig. 1.

Fig. 8 is a vertical sectional view taken through the tail end of the stapling arm.

Fig. 9 is a view showing the driver and anvil in extended positions.

Fig. 10 is a side view of the stapling arm as removed from its holder.

Fig. 11 is a fragmentary side view showing an alternate arrangement whereby the driver is held in extended position by a coil spring.

Fig. 12 is an enlarged fragmentary sectional view taken along line 12—12 of Fig. 9. The figure illustrates a latch means comprising a spring pressed ball.

Fig. 13 is a perspective view showing the spring employed in the arrangement of Fig. 12.

The stapling machine as shown in Figures 1 and 2 comprises a base which includes an anvil arm 10 and an anvil arm support 11. Resilient pads 12 act as

2

cushioning means for the base. An anvil 13 is mounted on the anvil arm. The anvil arm support 11 is rectangular in shape and closed at one end. The side walls of the anvil arm support 11 have closed slots 14 therein.

5 The top wall of stapling arm support 11 has a slot 15 which runs from the open end toward the closed end.

The automatic adjusting mechanism in the base consists of a spring member 16 which is contained in the anvil arm support and is secured to the closed end of the anvil arm support by a finger 17 which has been struck from the support casing and bent around one convolution of the spring 16. The spring 16 is secured at the other end to a pin 18 which passes through a spring housing 19 (Figure 5). The ends of the pin 18

15 engage with the slots 14 in the side walls of the anvil arm support 11. Flat spring members 20 (Figures 3, 12 and 13) are secured to opposite inside walls of the anvil arm 10 by means of fasteners 21. The flat springs 20

20 have a pin 22 fixed thereto which passes through holes 23 in the walls of the anvil arm 10 and ride in the slot

23 in the walls of the anvil arm 10 and ride in the slot 14. The spring members 20 have a dimple 24 (Fig. 12) which biases a ball bearing 25 against openings 26 in the walls of the anvil arm 10 which are smaller in diameter than that of the ball bearing in order to retain the

25 ball bearing between the flat spring 19 and the side walls of the anvil arm 10 yet allow the ball bearing to protrude beyond the exterior surface of the side wall of anvil arm 10.

The anvil arm 10 has a pall member 27 (Figures 2 and

30 3) connected thereto by means of a pivot pin 28. Pall member 27 travels in slot 15 (Figure 7) of anvil arm support 11. The pall member 27 is normally prevented from pivoting by a spring member 29 connected to the top wall of the anvil arm 10 by means of a rivet 30.

35 Brackets or ears 31 fixed to the anvil arm support 11 serve as bearings for a pivot pin 32. Brackets 31 are slotted as at 33 for a reason hereinafter described.

The stapling head support is comprised of a stapling arm 40 and a stapling arm support 41. A driving mechanism (not shown) is encased within stapling head 42 and is operated by a plunger 43 to which is secured a striking button 44. A conventional spring staple feed member 45 (Figure 3) is guided on a staple feed channel 46 (Figure 6) and operates to feed staples not shown into the staple driving head 42. The staple feed channel 46 has flanges 47 which permit the channel to be centered within stapling arm 40, in a manner well known in the art.

The side walls of the stapling arm support 41 have closed slots 14' therein similar to those of the anvil arm support 11. The top and bottom walls of stapling arm support 41 have slots 49 and 15' (Figure 6) respectively which run from the open end toward the closed end. Spring staple feed member 45 travels in slot 49.

55 The automatic feed mechanism heretofore described in conjunction with anvil arm 10 and anvil arm support 11 is identical with that used with stapling arm 40 and stapling arm support 41. A spring member 16' (Figure 2) similar to spring member 16 is contained in the

60 stapling arm support 41 and is secured to the closed end of the stapling arm support by a finger 17' which has been struck from the support casing and bent around one convolution of the spring 16'. The spring 16' is secured at the other end to a pin 18' which passes through a spring housing 19'. The ends of the pin 18' engage with the slots 14' in the side walls of the stapling arm support 41. Flat spring members 20' are secured to opposite inside walls of the stapling arm 40 by means of fasteners 21'. The flat springs 20' have a pin 22'

65 fixed thereto which passes through holes 23' in the walls of the stapling arm 40 and rides in slots 14'. The spring members 20' have a dimple 24' which biases a ball bearing 25' against openings 26' in the walls of the stapling arm 40 which are smaller in diameter than that of the ball bearing in order to retain the ball bearing between the flat spring 20' and the side walls of the stapling arm 40 yet allow the ball bearing to protrude beyond the exterior surface of the side walls of stapling arm 40.

75 The stapling arm 40 has a pall member 27' (Figure 8) connected thereto by means of pivot pin 28'. The pall member is normally prevented from pivoting by a spring

member 29' connected to the bottom wall of the stapling arm 40 by means of a rivet 38'. Pall member 27' travels in slot 15' (Figure 6) of stapling arm support 41. Brackets or ears 31' fixed to the stapling arm support 41 are pivotally supported upon pivot pin 32. Brackets 31' are slotted as at 33' for a reason hereinafter described. One of the brackets 31' acts as a stop for a stop lug 51 on one of brackets 31' thereby limiting the rearward pivotal movement of the stapling arm support 41 relative to the anvil arm support 11. A U-shaped spring member 52 having flanges 53 and 53' is positioned between the brackets 31 and 31' and connected to the brackets through pins 54 and 54' which engage the slots 33 and 33' respectively. Pins 54 and 54' are secured to spring 52 by welding or any manner obvious to the skilled craftsman. It is also obvious that pins 54 and 54' could be fashioned integrally with spring 52 from a single blank of material.

Operation

By pressing forward on U-shaped spring member 52 pins 54 and 54' riding in slots 33 and 33' are cammed toward each other. This camming action permits flanges 53 and 53' which normally engage palls 27 and 27' to be disconnected therefrom by action of springs 29-29'. Upon disengagement of palls 27 and 27' from flanges 53 and 53', springs 16 and 16' which are under tension, thrust forward anvil arm 10 and stapling arm 40 to the position shown in Fig. 9. Ball bearings 25 and 25' ride over the end portions of anvil arm support 11 and stapling arm support 41 to lock the anvil arm 10 and the stapling arm 40 in extended position (Figure 12).

The machine is recocked by merely grasping the stapler at both ends and shoving the arms and the arm supports together. The ball bearings 25 and 25' which are spring biased will readily disengage from the ends of the arm supports. The pall members 27 and 27' will pivot to ride past flanges 53 and 53' on U-shaped spring member 52. Once past flanges 53 and 53', pall members 27 and 27' will pivot back again to engage flanges 53 and 53' thereby recocking springs 16 and 16' for future use.

It is to be noted that the anvil arm or the stapling arm can be released individually by downward or upward pressure respectively, on U-shaped spring member 52. Such pressure cams only one of the pins 54 and 54'.

Figure 11 shows a modification of the stapling machine in which a spring member 60 encased in stapling arm support 41 acts to keep the stapling arm 40' in extended position. This modification requires a spring longer than spring 16 and spring 16' and avoids the necessity of having ball bearings 25 and 25' and the openings 26 and 26' associated therewith. With these exceptions the machine is identical with that described above.

Removal of the anvil arm or stapling arm

Pins 22 and 22' which travel in slots 14 and 14' and which prevent disengagement of the arms 10 and 40 from the arm supports 11 and 41, may be depressed and disengaged from slots 14 and 14' permitting arms 10 and 40 to be disconnected from arm supports 11 and 41. Fig. 10 shows the stapling arm 40 disconnected from the stapling arm support 41.

While the invention has been described in connection with different embodiments thereof, it will be understood that it is capable of further modification, and this application is intended to cover any variations, uses, or adaptations of the invention following, in general, the principles of the invention and including such departures from the present disclosure as come within known or customary practice in the art to which the invention pertains, and as may be applied to the essential features hereinbefore set forth and as fall within the scope of the invention or the limits of the appended claims.

Having thus described my invention, what I claim is:

1. An adjustable stapling machine comprising an anvil arm, an anvil on said anvil arm, a guide pin connected to said anvil arm, a stapling arm carrying a driving head and a magazine, a guide pin connected to said stapling arm, arms connected to, and extending rearwardly from said anvil arm and said stapling arm respectively, means for pivotally mounting said last mentioned arms together; said last mentioned arms having closed slots to receive said guide pins for movements therein,

and resilient means located in said last mentioned arms normally under compression which when released simultaneously move said anvil arm and said stapling arm from a retracted to an extended position to change the distance between the pivot means and the anvil and between the pivot means and the driving head.

2. An adjustable stapling machine comprising an anvil arm, an anvil on said anvil arm, a stapling arm carrying a driving head and a magazine, arms connected to and extending rearwardly from said anvil arm and said stapling arm respectively, means for pivotally mounting said last mentioned arms together, and resilient actuating means located in said last mentioned arms normally under compression which when released simultaneously move said anvil arm and said stapling arm from a retracted to an extended position to change the distance between the pivot means and the anvil and between the pivot means and the driving head.

3. An adjustable stapling machine comprising an anvil arm, an anvil on said anvil arm, a guide pin connected to said anvil arm, a stapling arm carrying a driving head and a magazine, a guide pin connected to said stapling arm, arms telescopically connected to and extended rearwardly from said anvil arm and said stapling arm respectively, means for pivotally mounting said last mentioned arms together, said last mentioned arms having closed slots to receive said guide pins, spring means interposed between said anvil arm and the arm on which said anvil arm is telescoped to move said anvil arm to an extended position to change the distance between the pivot means and the anvil, and spring means interposed between said stapling arm and the arm on which said stapling arm is telescoped to move said stapling arm to an extended position to change the distance between the pivot means and the driving head.

4. An adjustable stapling machine comprising an anvil arm, an anvil on said anvil arm, a stapling arm carrying a driving head and a magazine, arms telescopically connected to and extending rearwardly from said anvil arm and said stapling arm respectively, means for pivotally mounting said last mentioned arms together, catches carried by said anvil arm and said stapling arm, means carried by said pivot means normally engaging said catches when said anvil arm and one of said last mentioned arms and said stapling arm and the other of said last mentioned arms are telescoped, said engaging means being movable to a disengaged position, and means mounted between said anvil arm and said one of said last mentioned arms and between said stapling arm and said other of said last mentioned arms for urging said anvil arm and said stapling arm to a forward position when said catches are disengaged from said engaging means.

5. An adjustable stapling machine comprising an anvil arm, an anvil on said anvil arm, a stapling arm carrying a driving head and a magazine, arms telescopically connected to and extending rearwardly from said anvil arm and said stapling arm respectively, means for pivotally mounting said last mentioned arms together, catches carried by said anvil arm and said stapling arm, means carried by said pivot means normally engaging said catches when said anvil arm and one of said last mentioned arms and said stapling arm and the other of said last mentioned arms are telescoped, said engaging means being movable to a disengaged position, means mounted between said anvil arm and said one of said last mentioned arms and between said stapling arm and said other of said last mentioned arms for urging said anvil arm and said stapling arm to a forward position when said catches are disengaged from said engaging means, and means for locking said anvil arm and said stapling arm in the forward position.

6. An adjustable stapling machine comprising an anvil arm, an anvil on said anvil arm, a stapling arm carrying a driving head and a magazine, arms telescopically connected to and extending rearwardly from said anvil arm and said stapling arm respectively, means for pivotally mounting said last mentioned arms together, catches carried by said anvil arm and said stapling arm, means carried by said pivot means normally engaging said catches when said anvil arm and one of said last mentioned arms and said stapling arm and the other of said last mentioned arms are telescoped, said engaging means being movable to a disengaged position, and means mounted between said anvil arm and said one of said last men-

tioned arms and between said stapling arm and said other of said last mentioned arms for urging said anvil arm and said stapling arm to a forward position when said catches are disengaged from said engaging means, said urging means serving to maintain said anvil arm and said stapling arm in the forward position.

7. An adjustable stapling machine comprising an anvil arm, an anvil on said anvil arm, a stapling arm carrying a driving head and a magazine, arms connected to and extending rearwardly from said anvil arm and said stapling arm respectively, means for pivotally mounting said last mentioned arms together, said last mentioned arms telescopically supporting said anvil arm and said stapling arm respectively, means preventing said last mentioned arms from being disconnected from said anvil arm and said stapling head, means located in said last mentioned arms which when released move said anvil arm and said stapling arm to change the distance between the pivot means and the anvil and between the pivot means and the driving head, and means permitting said last mentioned arms to be disconnected from said anvil arm and said stapling head respectively.

8. An adjustable stapling machine comprising an anvil arm, an anvil on said anvil arm, a stapling arm carrying a driving head and a magazine, arms telescopically connected to and extending rearwardly from said anvil arm and said stapling arm respectively, means pivotally mounting said last mentioned arms together, said pivot means having slots therein, catches on said anvil arm, and said stapling arm respectively, means mounted in the slots in said pivot means normally engaging said catches when said anvil arm and one of said last mentioned arms and said stapling arm and the other of said last mentioned arms are telescoped, said engaging means being movable in said slots to a disengaged position, and means mounted between said anvil arm and said one of last mentioned arms and between said stapling arm and said other of said last mentioned arms for urging said anvil arm and said stapling arm to a forward position when said catches are disengaged from said engaging means.

9. An adjustable stapling machine comprising an anvil arm, an anvil on said anvil arm, a stapling arm carrying a driving head and a magazine, arms telescopically connected to and extending rearwardly from said anvil arm and said stapling arm respectively, means pivotally mounting said last mentioned arms together, said means having slots therein, catches carried by said anvil arm and said stapling head respectively, a U-shaped spring member having supporting means slidably mounted in the slots in said pivot means, said U-shaped spring member normally engaging said catches when said anvil arm and one of said last mentioned arms and said stapling arm and the other of said last mentioned arms are telescoped, and means mounted between said anvil arm and said one of said last mentioned arms and between said stapling arm and said other of said last mentioned arms for urging said anvil arm and said stapling head to a forward position when said catches are disengaged from said U-shaped spring member as said U-shaped spring members supporting means are moved forwardly in said slots.

10. An adjustable stapling machine comprising an anvil arm, an anvil on said anvil arm, a stapling arm carrying a driving head and a magazine, arms telescopically connected to and extending rearwardly from said anvil arm and said stapling arm respectively, means pivotally mounting said last mentioned arms together, said means having slots therein, catches carried by said anvil arm and said stapling arm respectively, a U-shaped spring member having supporting means slideably mounted in the slots in said pivot means normally engaging said catches when said anvil arm and one of said last mentioned arms and said stapling arm and the other of said last mentioned arms are telescoped, and means mounted between said anvil arm and said one of said last mentioned arms and between said stapling arm and said other of said last mentioned arms for urging said anvil arm and said stapling arm to a forward position when said catches are disengaged from said U-shaped spring member as said U-shaped spring member supporting means are moved forwardly in said slots, said U-shaped spring member urging said last mentioned arms in contradirections about said pivot means to maintain said anvil and said driver in spaced relation.

11. An adjustable stapling machine comprising an anvil arm, an anvil on said anvil arm, a stapling arm

carrying a driving head and a magazine, arms telescopically connected to and extending rearwardly from said anvil arm and said stapling arm respectively, means pivotally mounting said last mentioned arms together, said pivot means having cam surfaces thereon, catches carried by said anvil arm and said stapling arm respectively, a cam member movably mounted on said pivot means normally engaging said catches when said anvil arm and one of said last mentioned arms and said stapling arm and the other of said last mentioned arms are telescoped; said cam member cooperating with said cam surfaces, and means mounted between said anvil arm and said one of said last mentioned arms and between said stapling arm and said other of said last mentioned arms for urging said anvil arm and said stapling arm to a forward position when said catches are disengaged from said cam member as it is moved forwardly on the cooperating cam surfaces.

12. An adjustable stapling machine comprising an anvil arm, an anvil on said anvil arm, a stapling arm carrying a driving head and a magazine, arms connected to and extending rearwardly from said anvil arm and said stapling arm respectively, means for pivotally mounting said last mentioned arms together, resilient means for moving said anvil arm and said stapling arm from a retracted to an extended position with respect to said last mentioned arms, means for maintaining said anvil and stapling arms in extended position, means for maintaining said anvil and stapling arms in retracted position, releasing means for said retracted position maintaining means, and releasing means for said extended position maintaining means.

13. An adjustable stapling machine comprising an anvil arm, an anvil on said anvil arm, a stapling arm carrying a driving head and a magazine, arms connected to and extending rearwardly from said anvil arm and said stapling arm respectively, means for pivotally mounting said last mentioned arms together, spring means for moving said anvil arm and said stapling arm from a retracted to an extended position with respect to said last mentioned arms, means for maintaining said anvil and stapling arms in extended position, means for maintaining said anvil and stapling arms in retracted position, releasing means for said retracted position maintaining means, and releasing means for said extended position maintaining means.

14. An adjustable stapling machine comprising an anvil arm, an anvil on said anvil arm, a stapling arm carrying a driving head and a magazine, arms connected to and extending rearwardly from said anvil arm and said stapling arm respectively, means for pivotally mounting said last mentioned arms together, spring means for simultaneously moving said anvil arm and said stapling arm from a retracted to an extended position with respect to said last mentioned arms, means for maintaining said anvil and stapling arms in extended position, means for maintaining said anvil and stapling arms in retracted position, releasing means for said retracted position maintaining means, and releasing means for said extended position maintaining means.

15. An adjustable stapling machine comprising an anvil arm, an anvil on said anvil arm, a stapling arm carrying a driving head and a magazine, arms connected to and extending rearwardly from said anvil arm and said stapling arm respectively, means for pivotally mounting said last mentioned arms together, resilient means for moving said anvil arm and said stapling arm from a retracted to an extended position with respect to said last mentioned arms, means for maintaining said anvil and stapling arms in retracted position, and releasing means for said retracted position maintaining means.

16. An adjustable stapling machine comprising an anvil arm, an anvil on said anvil arm, a stapling arm carrying a driving head and a magazine, arms connected to and extending rearwardly from said anvil arm and said stapling arm respectively, means for pivotally mounting said last mentioned arms together, spring means for moving said anvil arm from a retracted to an extended position with respect to its rearwardly extending arm, spring means for moving said stapling arm from a retracted to an extended position with respect to its rearwardly extending arm, means for maintaining said anvil arm in retracted position, releasing means for said anvil arm retracted position maintaining means, means for maintaining said stapling arm in retracted position, and releasing

means for said stapling arm retracted position maintaining means.

17. An adjustable stapling machine comprising a base, an anvil on said base, a stapling arm carrying a driving head and a magazine, an arm connected to and extending rearwardly from said stapling arm, means for pivotally mounting said last mentioned arm and said base together, spring means for moving said stapling arm from a retracted position to an extended position with respect to said last mentioned arm, means for maintaining said stapling arm in retracted position, releasing means for

said stapling arm retracted position maintaining means, means for maintaining said stapling arm in an extended position, and releasing means for said stapling arm extended position maintaining means.
